UNITED STATES PATENT OFFICE.

CHARLES H. COLVIN, OF BROOKLYN, NEW YORK, ASSIGNOR TO THE SPERRY GYROSCOPE COMPANY, OF BROOKLYN, NEW YORK, A CORPORATION OF NEW YORK.

DESIGN FOR A POCKET-COMPASS CASING.

53,889.

Specification for Design.

Patented Oct. 7, 1919.

Application filed November 21, 1918. Serial No. 263,627. Term of patent 7 years.

To all whom it may concern:

Be it known that I, CHARLES H. COLVIN, a citizen of the United States of America, residing at 61 Poplar street, Brooklyn, in the county of Kings and State of New York, have invented a new, original, and ornamental Design for Pocket-Compass Casings, of which the following is a specification, reference being had to the accompanying drawing, forming a part hereof.

Figure 1 is a perspective view of the pocket compass casing. Fig. 2 is a side elevation thereof and Fig. 3 a front elevation. Fig. 4 is a plan view of the same.

The casing 1 is formed with a substantially pear-shaped section in plan as indicated in Fig. 1 with a lens 2 at its smaller end through which the compass rose 3 may be observed. In side elevation and in front elevation the casing is substantially rec-

tangular in shape being in both instances of less height than width and being in the side elevation of greater width than in the front elevation. The casing is provided with a transparent cover plate 10 through which may be seen the top of the compass rose 11 upon which suitable indicating marks 12 are placed. A reference marker 13 is provided on the top of the compass. The mounting for the lens is knurled as shown at 16 so that it may be turned to adjust the position of the lens.

Having described my new and original design what I claim and desire to secure by Letters Patent is:

The ornamental design for a pocket compass casing, as shown and described.

In testimony whereof I have affixed my signature.

CHARLES H. COLVIN.
